UNITED STATES PATENT OFFICE.

PETER A. COUPAL, OF SOUTH BOSTON, MASSACHUSETTS, ASSIGNOR OF ONE-HALF TO
JOHN W. O'NEILL, OF LYNN, MASSACHUSETTS.

LASTING-PINCERS.

1,009,478.

Specification of Letters Patent. Patented Nov. 21, 1911.

Application filed August 8, 1910. Serial No. 576,055.

To all whom it may concern:

Be it known that I, PETER A. COUPAL, a citizen of the United States, residing at South Boston, in the county of Suffolk and 5 State of Massachusetts, have invented new and useful Improvements in Lasting-Pincers, of which the following is a specification.

This invention relates to improvements in 10 pincers and particularly to improved lasting pincers.

One object of my invention is to provide strong and serviceable but readily separable means for attaching the jaws to the handle 15 levers so that the jaws when worn may be replaced by new ones.

Another object is to provide strong and serviceable but readily separable means for attaching the hammer face to the pincers.

20 Still another object is to provide for the strengthening of the handle levers adjacent to the pivot.

To these ends, the invention consists in the novel features of construction and in the 25 combination and arrangement of parts set forth in the following specification and particularly pointed out in the claims.

Referring to the drawing: Figure 1 is an 30 elevation of a pair of lasting pincers embodying my invention. Fig. 2 is an elevation of the pincers as viewed from the right hand side of Fig. 1. Fig. 3 is a sectional view taken on line 3-3 of Fig. 1. Fig. 4 is a sectional view taken on line 4-4 of Fig. 35 2. Fig. 5 is a sectional view taken on line 5-5 of Fig. 1.

Like numerals refer to like parts throughout the several views of the drawing.

In the drawing, 10 and 11 are two handle 40 levers crossed and pivoted to each other by a pivot 12 in the usual manner. These handle levers, for the sake of increased strength, are provided, respectively, with strengthening 45 ribs 13 and 14, one on each face of the pincers, the handle lever 11 being provided with a lateral recess 15 to receive the rib 13 and the handle lever 12 being provided with a lateral recess 16 to receive the rib 14, as shown best in Fig. 5. These ribs extend to 50 a considerable distance beyond the pivot to-

ward the free ends of the handles and thus greatly strengthen the handles and prevent them from bending, as most pincers do, at these points.

The handle lever 10 is provided with a 55 detachable jaw 17 and the handle lever 11 is provided with a detachable jaw 18, these jaws being made detachable so that when the corrugations on their inner co-operating faces become badly worn, the jaws may be 60 readily replaced by new ones, thus effecting a great saving, since it is usually necessary to throw lasting pincers away after they have become badly worn. To this end, the jaw 17 is provided with a transverse groove 65 19 and with a transverse tongue 20 and, similarly, the handle lever 10 is provided with a transverse groove 21 and a transverse tongue 22, the tongue 20 being fitted into the groove 21 and the tongue 22 being fitted into the 70 groove 19, these tongues and grooves forming complementary interengaging L-shaped lugs.

The jaw 17 is held in place on the handle lever 10 by a screw 23 preferably extending 75 obliquely through said jaw into said lever. This screw prevents lateral displacement of the jaw upon the lever in either direction. Similarly, the jaw 18 is provided with a transverse groove 24 and with a transverse 80 tongue 25 and the handle lever 11 is provided with a transverse groove 26 and a transverse tongue 27, the tongue 25 being fitted into the groove 26 and the tongue 27 being fitted into the groove 24, these parts thus constituting 85 complementary interengaging L-shaped lugs. In the manufacture of the pincers, these lugs and grooves are very readily formed by milling or planing cutters carried there-across in an obvious manner, this step in 90 the process of manufacture being very simple and inexpensive and the resultant structure being exceedingly strong, there being not the slightest yielding of the jaws even after a long and severe service. 95

The jaw 18 is held in place on the handle lever 11 by a screw 28 preferably extending obliquely from said lever into said jaw. The jaws 17 and 18 are provided with the usual corrugations, as shown, and when these cor- 100

rugations become so badly worn that it would otherwise be necessary to throw the pincers away, the jaws may be readily removed by the simple removal of the screws 5 23 and 28 and new jaws substituted for the old ones. In this way, a considerable saving is effected.

The handle lever 10 is provided with a hammer 29 having a removable face 30 which is provided, as usual, with corrugations 31. When this hammer face becomes badly worn, it is desirable to have it readily removable so that it may be replaced by another and yet it will be understood that the 15 mode of attachment must be such as to insure great rigidity and strength. To this end, the hammer face 30 is provided with a dovetailed tongue 32 which, as clearly shown in Fig. 3, extends only part way across this 20 tongue fitting into a corresponding dovetailed groove 33 which also extends only part way across the hammer 29.

In practice, in the manufacture of the tool, the groove 33 is milled by an end milling cutter of the proper cross sectional form. The tongue 32 is provided with a longitudinal hole 34 which receives a screw 35 having screw-threaded engagement with the body of the hammer 29, as shown in Fig. 3. 30 Preferably, the tongue 32 is provided with a longitudinal slot 36 communicating with the hole 34, as shown in Fig. 4, and the screw 35 is provided with a tapered head 37 fitting a corresponding taper provided in the hole 34 so that when the screw is rotated in the proper direction, it will draw the tongue 32 up against the end of the groove 33 and further movement of said tongue being then impossible, continued rotation of the screw 40 results in its tapered head 37 acting to expand the tongue 32 laterally so as to firmly engage the sides of the groove 33 and prevent any looseness. The hammer face when thus secured is as strong and rigid as if it 45 were an integral construction and yet the face may be removed and replaced by another with great facility.

Thus the pincers have all the advantages of ordinary pincers of integral construction 50 and yet have the added advantage over the ordinary pincers in that the jaws and hammer face when worn may be very readily replaced by new ones.

Having thus described my invention, what 55 I claim and desire by Letters Patent to secure is:

1. Pincers having, in combination, a pair of handle levers, and a pair of jaws mounted on said handle levers, respectively, said levers being respectively provided with opposed transverse tongues extending toward each other, said levers being also provided with opposed transverse grooves, and said jaws being respectively provided with 60 tongues extending in opposite directions and 65

respectively located in said grooves, and said jaws being respectively provided with grooves each having two opposite faces in which grooves said opposed tongues of said levers are respectively located. 70

2. Pincers having, in combination, a pair of handle levers, a pair of jaws mounted on said handle levers, respectively, said handle levers being provided, respectively, with complementary L-shaped lugs having opposed tongues extending toward each other, and means to hold said jaws against lateral displacement relative to their respective handle levers. 75

3. Pincers having, in combination, a pair of handle levers, a pair of jaws mounted on said handle levers, respectively, said levers being respectively provided with opposed transverse tongues extending toward each other, said levers being also provided with 80 opposed transverse grooves, and said jaws being respectively provided with tongues extending in opposite directions and respectively located in said grooves, and said jaws being respectively provided with grooves 85 each having two opposite faces in which grooves said opposed tongues of said levers are respectively located, and fastening means extending obliquely from said handle lever into said jaw. 90

4. In combination, a handle member and a work-performing member one of which is provided with a groove extending part way thereacross and the other of which is provided with a tongue located in said groove, 100 and means to force said tongue longitudinally into said groove and expand said tongue transversely in said groove. 95

5. In combination, a handle member and a work-performing member one of which is 105 provided with a groove and the other of which is provided with a longitudinally split tongue located in said groove, and a screw having a tapered portion to expand said split tongue in said groove. 110

6. In combination, a handle member and a work-performing member one of which is provided with a groove extending part way thereacross and the other of which is provided with a tongue interlocking with said 115 groove, said tongue being provided with a longitudinal slot, and a screw extending longitudinally through said tongue and having screw-threaded engagement with said grooved member, said screw having a tapered portion to expand said tongue in said groove. 120

7. In combination, a handle member and a work-performing member one of which is provided with a groove extending part way thereacross and the other of which is provided with a tongue dovetailed into said 125 groove, said tongue being provided with a longitudinal slot, and provided also with a tapered hole extending longitudinally of 130

and communicating with said slot, and a screw located in said hole and having screw-threaded engagement with said grooved member.

- 5 8. A handle member and a work-performing member one of which is provided with a groove extending part way thereacross and the other of which is provided with a tongue dovetailed into said groove, said tongue being provided with a longitudinal hole, and

a screw located in said hole and adapted to draw said tongue into said groove.

In testimony whereof I have hereunto set my hand in presence of two subscribing witnesses.

PETER A. COUPAL.
